UNITED STATES PATENT OFFICE.

AARON B. MOE, OF CHICAGO, ILLINOIS, ASSIGNOR TO OTIS & MOE MANUFACTURING COMPANY, A CORPORATION OF ILLINOIS.

DESIGN FOR A FEEDER.

46,288.

Specification for Design. Patented Aug. 18, 1914.

Application filed April 30, 1914. Serial No. 835,538. Term of patent 7 years.

To all whom it may concern:

Be it known that I, AARON B. MOE, a citizen of the United States, residing at Chicago, in the county of Cook and State of Illinois, have invented a new, original, and ornamental Design for a Feeder, of which the following is a specification, reference being had to the accompanying drawing, forming part thereof.

Figure 1 is a plan view of a feeder illustrating my new design, and Fig. 2 is a central vertical section thereof.

I claim:

The ornamental design for a feeder as shown.

In witness whereof, I have hereunto subscribed my name in the presence of two witnesses this 27th day of April 1914.

AARON B. MOE.
